EMASCULATOME

Harry O. Snouffer, Deer Creek, Okla.

Application March 25, 1933. Serial No. 662,734

6 Claims. (Cl. 128—306)

This invention relates to an improved and structurally refined veterinary's emasculatome such as is used for castrating animals.

Generally stated, the improved instrument in which my advantageous features are embodied is of the well-known pincers type. Admittedly, this form of emasculatome is more or less universally employed in a well-known manner for pinching or crushing the spermatic cord in a bloodless manner and without developing an objectionable wound in the scrotum.

It is a matter of common knowledge however that the pincers type emasculatome, as well as the wrench type is not altogether fool-proof and successful in its completeness of action due to the accidental slippage of the spermatic cord at the time it is supposedly pressed between the crushing jaws.

I am aware of the fact that it is not broadly new to provide a supplemental means to aid in holding the cord effectively in place while performing the operation. Notwithstanding these previous attempts to solve the problem of successfully holding the cord while performing this delicate task, I have evolved and produced an appreciable contribution to the art which, to my mind, is more positive and dependable in action, insures more expeditious and effective results, and better fulfills the requirements of an instrument of this classification.

Other features and advantages of the invention will become more readily apparent from the following description and drawings.

In the drawings:

Figure 1 is an enlarged perspective view illustrating the essential features of the unique cord holding and retaining means constituting the principal novelty of the invention.

Figure 2 is a view in section and elevation showing the complete tool with the cord grasping jaws closed and the master or severing jaws approaching a substantially closed position.

Figure 3 is a front end elevation of the jaw arrangement depicted in Figure 2.

Figure 4 is a detail perspective view.

Figure 5 is a view similar to Figure 2 showing both sets of jaws wide open to permit insertion of the testicles.

Figure 6 is a view showing the final step wherein both sets of jaws are positively closed.

I will first describe the well known pincers type castrating instrument or emasculatome as it is generally known in the trade and profession. To begin with, the numeral 7 designates the conventional operating levers having handgrips 8

and having their opposite end portions pivotally joined together as at 9. The main or master cord severing jaws as they are known in the trade are denoted by the numerals 10 and terminate in the customary fashioned blunt gripping edges 11.

These jaws are pivotally attached to each other in companion relationship as indicated at 12 and have their shank portions 13 pivotally connected as at 14 to the adjacent end portions of the levers 7 outwardly of the main pivot 9. There is absolutely nothing new in this type of an instrument.

In accordance with my invention, I provide a pair of duplicate attaching lugs or ears 15 on the inner peripheral portion of the jaws 10 at points adjacent to and on opposite sides of the pivot 12. These lugs are adapted to accommodate the supplemental cord grasping and holding jaws 16. These jaws 16 are of arcuate or segmental formation and have their attached ends bifurcated with the furcations straddling and pivotally attached to the lugs 15 as indicated at the points 17.

It will be noticed that the curvature of the jaws 16 is slightly more acute than the jaws 10 and that the jaws 16 are confined wholly within the limits of the jaws 10. Moreover, the abutting free swingable edge portion 18 of these supplemental jaws are fashioned to come together in firm contacting relationship as is obvious from the configuration illustrated in Figure 1. Then too, the edge portions 18 are provided with co-operating notches 19 which are brought together in matched relationship to provide a sort of a keeper for the spermatic cord. The numeral 20 designates spring retention studs carried by the intermediate outer faces of the jaws 16 and located to accommodate the inner ends of the coiled expansion and compensating springs 21.

The outer ends of the springs 20 are located in sockets formed in the intermediate inner faces of the jaws 10 as shown in Figure 2, the springs co-operating with reduced terminals 22 carried by the spring adjusting set screws 23. Manifestly the set screws are threaded through openings in alignment with the sockets and under this arrangement it is permissible to regulate the tension of the springs 21 to the requisite sensitivity of action.

Under this arrangement the cord holding or supplementary jaws 16 are maintained in substantially spaced parallelism with respect to the jaws 10 and as before stated the curvature of said jaws 16 is such that they come together

in cord gripping relationship prior to the final closing of the jaw-ends 11. This progressive action is important. Moreover, the compensating action of the springs 21 is important to the extent that it allows the jaws 16 to react with the desired cushioning and yieldable effect such as would not be had if the two sets of jaws 10 and 16 were rigidly connected together for operation in unison.

- 10 Moreover, the introduction of the springs 21 between the respective jaws allows the jaw ends 11 to come into effective biting relationship without necessarily forcing the jaws 16 together in an undesirable rigidly crushing manner. Even 15 if the jaws 16 are pressed together firmly because of improper adjustment of the respective jaws 10 and 16, the registering notches 19 afford the desired clearance action for the spermatic cords.
- 20 It is apparent that when the levers 7 are spread apart in the relationship depicted in Figure 5 both sets of jaws 10 and 16 are equally spread apart to permit initial placement of the instrument. Then by moving the levers together the 25 jaws are simultaneously moved together in the desired intermittent manner so that when the levers 7 are in the position shown in Figure 2 the jaws 16 have been brought together sufficiently close to grasp and hold the spermatic cord whereby when the levers approach the relationship shown in Figure 6 the jaw-ends 11 will come into proper cord severing or crushing action.

30 It is thought from the foregoing description that the advantages and novel features of the invention will be readily apparent. It is to be understood that changes may be made in the construction and in the combination and arrangement of the several parts provided that such changes fall within the scope of the appended claims.

I claim:

- 35 1. An emasculatome of the class described comprising a pair of pivotally connected cord crushing jaws, operating levers for said jaws, and a pair of duplicate spring-pressed cord holding elements carried by said jaws, and compensating spring means associated with the jaws and said elements to bring the effective portions of said 40 elements into cord engaging and holding relationship prior to the final closing action of the jaws.

45 2. An emasculatome of the class described comprising a pair of pivotally connected cord crushing jaws, a pair of operating levers for said jaws, and a pair of adjustably mounted supplementary jaws carried by the first named jaws and co-operating with the inner peripheral surfaces of said jaws, said supplementary jaws being mounted to move into initial cord holding relationship prior to the final closing of the first-named jaws.

50 3. A pincers type emasculatome comprising a pair of pivotally connected substantially semi-circular master cord crushing jaws, a pair of operating levers for said jaws, a pair of supplementary smaller cord engaging and retaining jaws pivotally attached to the inner portions of said first-named jaws.

55 4. A pincers type emasculatome comprising a pair of pivotally connected substantially semi-circular master cord crushing jaws, a pair of operating levers for said jaws, a pair of supplementary smaller cord engaging and retaining jaws pivotally attached to the inner portions of said first-named jaws, the free ends of said supplementary jaws being notched to form an opening 90 to accommodate the spermatic cord.

60 5. A pincers type emasculatome comprising a pair of pivotally connected substantially semi-circular master cord crushing jaws, a pair of operating levers for said jaws, a pair of supplementary smaller cord engaging and retaining jaws pivotally attached to the inner portions of said first-named jaws, the free ends of said supplementary jaws being notched to form an opening 100 to accommodate the spermatic cord.

65 6. A pincers type emasculatome comprising a pair of pivotally connected substantially semi-circular master cord crushing jaws, a pair of operating levers for said jaws, a pair of supplementary smaller cord engaging and retaining jaws pivotally attached to the inner portions of said first-named jaws, the free ends of said supplementary jaws being notched to form an opening 110 to accommodate the spermatic cord, and spring means interposed between the respective pairs of jaws to render the supplementary jaws substantially resilient in action.

70 7. A pincers type emasculatome comprising a pair of substantially semi-circular outer cord crushing jaws pivotally connected together, operating levers for said jaws, said jaws being provided on their inner surfaces at predetermined points with attaching lugs, a pair of opposed substantially semi-circular smaller supplementary jaws located within the limits of said first-named 120 jaws and pivotally attached at one end to said lugs, the free ends of said supplementary jaws being notched, coiled springs interposed between the respective opposed pairs of jaws, and spring tensioning means carried by the first-named 125 jaws.
